[57] CLAIM

The ornamental design for a combined chair and step, as shown and described.

DESCRIPTION

FIG. 1 is a front elevational view of the combined chair and

step with the support in a raised position to form the chair back;

FIG. 2 is a rear elevational view thereof;

FIG. 3 is a rear perspective view thereof;

FIG. 4 is a front perspective view thereof;

FIG. 5 is a right side elevational view, the left side being a mirror image thereof;

FIG. 6 is a top plan view thereof;

FIG. 7 is a side perspective view showing the support in an alternate transitional position as the support is lowered to form the step;

FIG. 8 is a front perspective view with the support in the lowered position;

FIG. 9 is a first rear perspective view thereof;

FIG. 10 is a second rear perspective view thereof;

FIG. 11 is a left side elevational view, the right side being a mirror image thereof;

FIG. 12 is a rear elevational view thereof;

FIG. 13 is a front elevational view thereof;

FIG. 14 is a top plan view thereof; and,

FIG. 15 is a bottom plan view thereof.
